(57) **CLAIM**

The ornamental design for a touch screen control panel, as shown and described.

DESCRIPTION

FIG. 1 is a front top perspective view of the touch screen control panel of the present invention.

FIG. 2 is a front view of the touch screen control panel of the present invention.

FIG. 3 is a rear top perspective view of the touch screen control panel of the present invention.

FIG. 4 is a rear view of the touch screen control panel of the present invention.

FIG. 5 is a left side view of the touch screen control panel of the present invention.

FIG. 6 is a right side view of the touch screen control panel of the present invention; and,

FIG. 7 is a bottom view of the touch screen control panel of the present invention.

The broken line showing of structural features is included for the purpose of illustrating non-claimed subject matter and forms no part of the claimed design.

1 Claim, 7 Drawing Sheets
